UNITED STATES PATENT OFFICE.

WILLIAM B. FRYE, OF BUFFALO, NEW YORK.

ATTACHMENT FOR OVERTHOES.

1,251,007.

Specification of Letters Patent. Patented Dec. 25, 1917.

Application filed March 19, 1917. Serial No. 155,648.

To all whom it may concern:

Be it known that I, WILLIAM B. FRYE, a citizen of the United States of America, residing in the city of Buffalo, county of Erie, 5 and State of New York, have invented a new and useful Attachment for Overshoes, of which the following is a full, clear, and exact description.

My invention relates generally to attachments for overshoes and more particularly to means for securely retaining the overshoe in position upon the shoe which is inserted therein.

It is well known that, heretofore, in order 10 to retain an overshoe in position, it has been necessary that it be of such a size and shape as to snugly fit the inserted shoe. This snug fit results in an objectionable pressure upon the foot of the wearer and many times, after 15 continued use, the overshoe stretches and becomes loose, with the result that it often drops off, thereby causing much inconvenience, and sometimes loss, to the wearer.

In my invention, I have sought to overcome 20 the disadvantages above noted by providing an attachment for overshoes whereby the overshoe, even though larger than the inner shoe (so as to be comfortable) may be securely fastened thereto. This is accomplished by providing a gripper, which is attached to the overshoe and arranged to engage with the breast of the heel of the inner shoe, thereby exerting a pressure between this point and the back of the overshoe.

Moreover, my device is such that it may be attached to any kind or size of overshoe.

The above objects and advantages have been accomplished by the device shown in the accompanying drawings, of which:

Figure 1 is a perspective view of my device.

Fig. 2 is a plan view of the blank from which my device is made.

Fig. 3 shows a fragmentary portion of an overshoe with my device attached.

Fig. 4 is a fragmentary sectional plan view taken on line 4—4 of Fig. 3.

Fig. 5 is a perspective view of a modified form of my device.

Fig. 6 is a plan view of the blank from which the last mentioned form is made.

Fig. 7 is a perspective view of another modification.

Fig. 8 is a fragmentary, sectional view showing the method of attaching the form 55 shown in Fig. 7.

Referring to the drawings and more particularly to Figs. 1 to 4 thereof, 10 is the blank from which the device shown in these figures is made. The blank is formed at 60 each corner with a diagonally arranged slit 11, whereby there is formed a body portion 12 and end portions 13 and 14. Between the end portions 13 and 14 and the sides of the blank, tines 15 are formed.

After the blank is cut, as shown in Fig. 2, the tines 15 are bent downwardly at right angles with the body portion 12; and the end portion 13 is bent upwardly at an angle with the body portion, which is preferably 70 less than a right angle. When the device is to be attached to the overshoe, it is placed within the heel of the same in such a position that the upper edge of the end portion 13 will engage with the breast of the shoe heel. 75 When in proper position the tines of the device are driven downwardly through the heel of the overshoe and clenched on the under side. When properly arranged, the upper edge of the end portion 13 will force the inner shoe against the back of the overshoe, thus securely holding it in position therein.

In making the form of device shown in Fig. 5, the blank (Fig. 6) is cut along lines 16, 17 and 18. The slits 16 and 17 sever one 85 blank from the next adjacent blank and form the outer boundaries of the end portion 19. The slits 18 form the tines 20. The tines 21 are formed when the end portion 19 of the next adjacent blank is cut. A body 90 portion 22 is formed between the tines 20 and 21. These tines are, as in the form first described, bent downwardly at right angles to the body portion 22. The end portion 19 is bent upwardly along a line drawn between the points of intersection of the slits 17 and 18, and at an angle which is less than a right angle.

The form of device shown in Fig. 7 is made from stock which is not slitted or cut, 100 but which is provided with a plurality of countersunk apertures 23 in the body portion 24 thereof. One end of the material forming the device is bent upwardly so as to form an end portion 25. When securing this 105 device in position, a bifurcated rivet 26 is

passed through each of the apertures 23 and through the heel of the overshoe, were it is clenched over, as shown in Fig. 8.

Having thus described my invention, what I claim is:

In an overshoe, a gripper comprising a flat body part positioned in the overshoe to act as a bearing plate for the heel of the inner shoe, said body part having a flat, re-

silient, upwardly and rearwardly bent end 10 portion, and means for securing the gripper to the heel of the overshoe, the heel of the inner shoe being frictionally held between the end portion and the back of the overshoe.

In testimony whereof, I have hereunto signed my name.

WILLIAM B. FRYE.
